FRANKLIN B. SHUSTER, OF NEW HAVEN, CONNECTICUT; LUILLA F. SHUSTER
ADMINISTRATRIX OF SAID FRANKLIN B. SHUSTER, DECEASED.

HELIX-COILING MACHINE.

1,023,099.

Specification of Letters Patent.

Patented Apr. 9, 1912.

Application filed October 28, 1910. Serial No. 589,563.

To all whom it may concern:

Be it known that I, FRANKLIN B. SHUSTER, citizen of the United States, residing at New Haven, in the county of New Haven 5 and State of Connecticut, have invented certain new and useful Improvements in Helix-Coiling Machines; and I do hereby declare the following to be a full, clear, and exact description of the invention, such as 10 will enable others skilled in the art to which it appertains to make and use the same.

My invention relates to machines for coiling wire, and it is particularly adapted for forming coils of larger diameter than the 15 coil supporting rod or arbor, and it consists in rotating said central support at the same rate of speed as the feed rolls, thus relieving the rolls of the extra power it would otherwise require to rotate a long and large coil 20 of wire mounted on a stationary support.

Referring to the drawings wherein like figures and letters of reference indicate like parts: Figure 1 represents a side elevation of the machine and broken view of one of 25 its legs, also a view of a partially formed coil and cross sectional view of the wire or rod as it is being fed through the rolls: Fig. 2 is a front elevation of the machine with the legs and tubular coil supporting 30 arbor removed; Fig. 3 is an enlarged detail broken view of the coil arbor and its supporting coupling removably secured to one of the feed roll shafts; Fig. 4 is an enlarged detail view of the arbor coupling; Fig. 5 35 is an enlarged end elevation of the coil supporting arbor and its roller bearing, and broken view of the adjustable stem supporting the roller bearing; Fig. 6 is an enlarged detail rear elevation of the breaking down 40 or pitch roll; Fig. 7 is an enlarged plan view of the pitch roll, sectional view of its supporting slide on line *a* of Fig. 2, also a view of the slide operating screw, and means for securing the pitch roll in any of its adjusted 45 positions; Fig. 8 is a diagram of the gearing located at the rear end of the machine for operating the feed rolls; and Fig. 9 is an enlarged sectional modified view of one of the feed rolls designed to support the inner 50 end of the coil supporting arbor.

The machine frame 1, mounted on the bed 2, carries the feed rolls 3, 4, 5 and 6, mounted on the shafts 7, 8, 9 and 10, shown at Fig. 8, driven by the gears 11, 12, 13 and 14. 55 The driving pulley 15 is mounted on the

main shaft 16 which also carries the driving pinion 17 meshing with the large gear 18 mounted on the feed roll shaft 9. Power is thus transmitted from the pinion 17 to the large gear 18, and from the gear 18 on the feed roll shaft 9 to the shaft 7 and through the intermediate gear 19, on stud 20, to the spindles or shafts of the other two feed rolls. The upper feed roll shafts are journaled in boxes 21 and 22 having a vertical 60 adjustment in the machine frame by the common method of the screws 23 and horizontally arranged gears 24 and 25. The shafts of the lower feed rolls are simply journaled in the machine frame. 65

26 is the breaking down or pitch roll rotatably mounted on the pintle 27, Fig. 7, and this pintle is longitudinally adjustable in the hole 28 of the slide 29, which slide has a longitudinal movement in the projection 1^a of the machine frame, Figs. 1 and 2, through the medium of the screw 30 and its hand wheel 31. The pintle 27, Figs. 6 and 7, is provided throughout its length with the angular groove 32 adapted to receive the pointed end of the rod 33 backed up by the screw 34. The pitch roll pintle is adjusted to and from the slide in order to place the pitch roll in proper relation to the feed rolls to form the coil 35 and give said coil 70 the required pitch as it leaves the feed rolls, and is secured in any such adjusted position by means of the before mentioned rod 33 and screw 34. 75

The coupling 36 has the bore 37 whose inner end is threaded to receive the threaded end 9^a of the feed roll shaft 9 shown at Fig. 3. The coupling 36 has the hub 36^a adapted to receive the inner end of the tubular coil supporting arbor 38, which inner end is provided with the bayonet slot 39 adapted to receive the pin 40 projecting from the hub of the coupling 36. The outer end of the arbor 38 rests on the rollers 41 mounted in the head 42, which rollers provide an anti-frictional bearing for the arbor 38 and thus prevent torsional strain of said arbor. The stem 43 of the roller head is made vertically adjustable in the standard 44 as shown 80 at Fig. 1. 85

As before mentioned, the machine is adapted to form coils of wire larger than the supporting arbor, and to do this, especially when large wire is used, it is absolutely necessary to rotate the coil supporting arbor 100 105 110

at the same rate of speed as the feed rolls in order to secure a uniform coil. With large wire, and a large coil of thirty inches or more in diameter, and a stationary arbor, the strain of forcing the wire through the pitch roll and rotating the coil over a long stationary arbor would cause the coil to buckle and thus distort it. But with a rotating arbor traveling at the same rate of speed as the feed rolls, the friction of the coils on the arbor is entirely eliminated, thus obviating any tendency of the coils to buckle. When a sufficient length of coil has been formed, the arbor is detached from the coupling 36 and the coil removed therefrom. The pin 40 serves as a driver for the arbor and the bayonet slot in the arbor furnishes an easy and convenient method of quickly attaching and detaching the arbor from the coupling.

In the modified construction shown at Fig. 9, the inner end of the coil supporting arbor is mounted on the hub 6^a of the feed roll 6, and the coupling is, in this case, dispensed with.

While I show the coil supporting arbor driven directly from one of the feed roll

shafts as the most direct and convenient method of driving it at the same rate of speed as the feed rolls, I hold myself at liberty to rotate the arbor in any well known suitable manner that will produce the desired result.

Having thus described my invention, what I claim is:—

A coiling machine comprising feed rolls and their shafts, an adjustable pitch roll, a coil supporting arbor rotatably and removably connected with one of the feed roll shafts, a roller bearing support for the opposite end of the arbor, said arbor substantially of the same diameter as the feed roll with which it alines, so that when coils are wound of larger diameter than the arbor, the coils will readily take to the arbor on leaving the feed roll and rotate with said arbor and thus reduce the strain on the feed rolls.

In testimony whereof I affix my signature in presence of two witnesses.

FRANKLIN B. SHUSTER.
